UNITED STATES PATENT OFFICE.

JOHN E. CARLSON, OF GARDNER, MASSACHUSETTS.

MACHINE FOR CUTTING REED.

Application filed April 11, 1923. Serial No. 631,456.

This invention relates to a machine for operating upon large rods or pieces of reed, forcing them through dies to produce a large number of reeds of relatively small diameter. In the operation of such machines, as heretofore known, the original rod or piece of reed is divided into a central core, a plurality of small reeds surrounding the core, and a number of pieces of waste formed from the outside of the rod. These several parts are discharged together from the machine, after which they require manual sorting and separation before any further operation can be performed.

It is one important object of my invention to provide mechanical means for automatically separating the three products of the machine as they are delivered from the cutting die, thus avoiding the necessity for manual separation.

Another object of my invention is to provide a machine in which a second feeding device engages the core as it leaves one die and advances it to a second die, thus providing continuous operation and greatly assisting the final movement of the extreme rear end portion of the rod through the first die.

Other features of my invention relate to arrangements and combinations of parts which will be hereinafter described and more particularly pointed out in the appended claims.

A preferred form of the invention is shown in the drawings in which—

Fig. 1 is a side elevation of my improved machine, with parts thereof shown in section;

Fig. 2 is an enlarged side elevation of the cutting die and its associated sorting and separating mechanism;

Fig. 3 is a detail view, looking in the direction of the arrow 3 in Fig. 2;

Fig. 4 is a transverse sectional elevation, taken along the line 4—4 in Fig. 1;

Fig. 5 is a detail view of a cutting die; and

Fig. 6 is a sectional view thereof.

Referring to the drawings, I have shown a reed cutting machine which embodies certain well known features of such machines. The large rod or piece of reed R is fed through a guide 10 to a feeding device comprising a cylindrical sliding member 11 movable by a yoke lever 12 which is regularly oscillated by a feed shaft 13, an eccentric 14, and an eccentric link or connect-

ing rod 15. A plurality of tapered feed bars 16 are mounted in inclined guide-ways 17 in the cylindrical member 11 and are drawn yieldingly rearward to engage the reed R 60 by springs 18.

As the feeding device is oscillated, the rod R is intermittently advanced toward a pair of yieldingly mounted centering jaws 20 (Fig. 4). The jaws 20 are mounted on 65 plungers 21 movable radially in bearing blocks 22. The bars 16 also have lateral extensions 23 and 24 which are connected by links 25 to equalizing levers 26 pivoted at 27 to a die-head or frame 28. A cord 29 70 is secured to the end of the lower equalizing member 26 and passes over a guide pulley 30 on the upper lever, said cord also supporting a weight T at its lower end. With this construction, the centering jaws 20 have 75 a straight line movement toward and from each other and are always at equal distances from the axis of the cutting die 31. The die 31 is secured in the head 28 by adjusting screws 32 and is provided with a central 80 opening 33, a plurality of small round intermediate openings 34 and a series of relatively large outer openings 35.

In the operation of the machine, the thoroughly moistened rod R is forced between 85 the centering jaws 20 and through the cutting die 31 which divides the rod into a central core C, a plurality of small reeds R' and a number of strips of waste W.

The construction and operation of the 90 machine as thus far described is of the usual type and forms no part of my present invention, which will now be described.

At the delivery side of the die 31, I provide a sorting and separating device comprising an outer conical member 40 held in place by a disc 41 fixed to the die head 28 by bolts 42 and having the small end of its cone abutting the die 31 between the outer openings 35 and the small reed cutting openings 34. The waste W passes outside of the conical member 40 while the reeds R' and the core C pass inside of the member 40. An inner conical member 43 is also positioned by the disc 41 and is provided with 95 a hollow cylindrical shank 44 centered in the disc. The small end of the conical member 43 engages the die 31 between the small circular openings 34 and the central opening 33. 100

The axial opening through the member 43 and shank 44 is of sufficient size to permit 110

free passage of the core C, while the reeds R' pass between the outer conical member 40 and the inner conical member 43. A portion 43^a (Fig. 2) of the member 43 is enlarged to fit closely within the conical member 40 and guides the reeds R' to one side of the member 43, where they are collected and discharged through an opening 45 in the disc 41. Obviously the member 43 and the disc 41 may be arranged to discharge the reeds R' in any desired direction.

My improved sorting and separating device thus prevents intermingling of the waste and core with the finished reed and delivers the three products separately, thus avoiding a large amount of manual labor.

While the machine as thus far described is an important improvement over the previous practice, a further feature of my invention relates to the provision of a second feeding device 50 (Fig. 1), mounted beyond the discharge end of the shank 44 and actuated by a yoke lever 51 connected by a link 52 to the yoke lever 12 and eccentric link 15. This feeding device 50 engages the core C and advances it through a bushing 53 to a second cutting die mounted in a second die head 54. A second sorting and separating device 55 is mounted on the die head 54 and corresponds in its several parts to the sorting device previously described, with the exception that the inner ends of the conical members are adapted to the different locations of the holes or openings in the second and smaller die. The waste W' is delivered outside the device 55, the reeds R² are collected and delivered through an opening in the end of the device 55 and a smaller core C² is delivered through the axial opening as previously described.

Where the reed is of sufficient size to require a third operation, a third feeding device 60, die head 61, and sorting device 62 may be provided, discharging additional waste W², reeds R³ and core C². Quite commonly the third cutting head 61 merely trims the core C, discharging it as a finished reed C³, and no reeds R³ are produced from the third cutting die.

Having described the construction and operation of my improved cutting machine, the advantages thereof will be apparent. The separate delivery of the finished reed and waste greatly reduces the manual labor and the continuous operation of the machine permits me to reduce a rough rod or piece of reed R to finished reeds R', R², R³ and C³ at a single operation and without manual attention, except to dispose of the finished reeds as they are sorted and delivered from the machine. Furthermore, each feeding device 51 and 60 acts to pull the rear end of the rod R through the preceding cutting die, as well as to push the remaining core through the next succeeding die. In

this way I avoid leaving a short end of rod in the machine or pushing the rear end of the rod through the machine by the next succeeding rod, an operation which has always been very unsatisfactory.

Having thus described my invention and the advantages thereof, I do not wish to be limited to the details herein disclosed otherwise than as set forth in the claims, but what I claim is:

1. A machine for cutting reeds comprising a cutting die, means to feed the work to the die, and means to separate the different products formed by the die, said separating means comprising a conical member mounted adjacent said die effective to separate the waste from the finished reeds, and means, including said member to assemble all the finished reeds for delivery at one side thereof.

2. A machine for cutting reeds comprising a cutting die, means to feed the work to the die, and means to separate the different products formed by the die, said separating means comprising a conical member mounted adjacent said die and effective to separate the waste from the finished reeds, and a second conical member mounted within said first conical member effective to separate the reeds from the remaining core, and means, including said member to assemble all the finished reeds for delivery at one side thereof.

3. A machine for cutting reeds comprising a cutting die, means to feed the work to the die, and means to separate the different products formed by the die, said separating means comprising a conical member mounted adjacent said die and effective to separate the waste from the finished reeds, and a second conical member mounted within said first conical member, said second member having a raised portion over a substantial section of its periphery engaging the inner wall of said first member and effective to assemble the reeds for delivery at one side of said member.

4. A machine for cutting reeds comprising a cutting die, means to feed the work to the die, and means to separate the different products formed by the die, said separating means comprising a conical member mounted adjacent said die and effective to separate the waste from the finished reeds, a second conical member mounted within said first conical member, said second member having an axial opening forming an outlet for the remaining core, and a guideway formed between said members effective to assemble the reeds for delivery at one side thereof.

5. A machine for cutting reeds comprising a cutting die, means to feed work to the die, means to separate the different products formed by the die, said separating means

comprising two concentrically mounted, conical members positioned adjacent said die, and means comprising a guide between the members and a plate slotted at one side 5 thereof, mounted on the outer end of said members, to assemble the finished reeds for delivery at one side of the machine.

6. A machine for cutting reeds comprising a series of cutting dies, a reciprocating 10 means to clamp and positively feed the work to the first die, means to separate the

products of each die, additional reciprocating clamping and feeding devices between each separating means and the next successive die, each such device being effective to 15 clamp and positively feed the core left by the preceding die, and actuating means for giving said clamping and feeding devices simultaneous movements.

In testimony whereof I have hereunto af- 20 fixed my signature.

JOHN E. CARLSON.
